UNITED STATES PATENT OFFICE.

HERMAN F. SWARTZ, OF EAST CLEVELAND, OHIO.

LAMP FOR PHOTOGRAPHIC DARK ROOMS.

SPECIFICATION forming part of Letters Patent No. 768,088, dated August 23, 1904.
Application filed June 22, 1903. Serial No. 162,466. (No model.)*To all whom it may concern:*

Be it known that I, HERMAN F. SWARTZ, of East Cleveland, in the county of Cuyahoga and State of Ohio, have invented certain new and useful Improvements in Lamps or Lanterns for Photographic Dark Rooms, of which the following is a specification.

The invention relates to a lamp for a photographic dark room.

Colored fluids have been demonstrated to be much more transparent to non-actinic light than are any known solids and at the same time to be perfectly homogeneous, and hence reliable.

The object of the present invention is to apply this fact to use in a lamp for a photographic dark room and to construct a lamp for such use in which a fluid color-filter is employed. I employ a cylindrical cell to contain the colored fluid, and inclosed within it is the source of light. Previous attempts to construct such a lamp have failed because the heat generated by the light employed has been too great for the fluid, particularly when oil or gas is used. I seek to overcome this difficulty by the use of a ventilator, whereby there is automatically secured a continuous cold blast against the top of the cell at the point where it would otherwise be the quickest to overheat.

The invention will now be fully described, having reference to the accompanying drawings, and the novel features thereof will be particularly pointed out in the claims at the close of the specification.

In the drawings, Figure 1 is a vertical section on line 1 1 of Fig. 2 of a lamp constructed according to my invention. Fig. 2 is a horizontal section on line 2 2 of Fig. 1. Fig. 3 is a plan. Fig. 4 is a modification showing the base fitted with an incandescent electric lamp. Fig. 5 shows the base as adapted for the use of oil.

1 represents the base on which is supported the annular cylindrical cell 2. The cell 2 should be of some transparent material, the word "transparent" being used in a broad sense of light-transmitting.

The lamp shown in the drawings is represented as being constructed for use with gas;

but the invention is also adapted for use with oil or electricity.

The gas-pipe 3 is shown as entering through the side of the base 1 and extending upward into the interior of the chamber 4 of the cell. 55 On the upper end of the gas-pipe is a burner 5. Either a "fish-tail" or annular burner--*e. g.*, Argand--may be used, with or without a chimney. The cell 2 contains a colored fluid 6, which acts as a filter for the light. Resting on the top of the annular walls of the cell is a ventilating-box 7, having an annular base 8 and a downwardly-extending annular flange 9, which fits inside of the inner wall of the cell and forms with the base 8 a screen to prevent the light from passing over the top of the filtering fluid. In the sides of the box 7 are lateral openings 10 for ventilation. Blinds 11 extend from one edge of the openings 10 diagonally inward and past the other edge of 70 the openings to prevent lateral escape of the light.

A flue 13, preferably of metal, passes up through the covered top of the ventilating-box 7. For lamps of large size the portion 75 of the flue within the ventilating-box may be made of double walls with asbestos packing. The luminant is located down within the body of the cell below the top, and the flue extends upward from the luminant, so that the draft 80 occasioned by the heat of the luminant and by the flue causes the cold air to be drawn down into the inner cylinder and up through the flue. The blinds 11 are so curved as to give a spiral direction to the incoming draft 85 of air, and this, together with the location of the luminant and flue, will cause the cool air to descend to the bottom of the lamp by a spiral motion closely hugging the inner wall of the inner cylinder, thus cooling the sides 90 as well as the top of the cylinder.

The flue is preferably made extensible, so as to permit regulation of the draft by varying the length of the flue, and to this end a pipe-section 14 is telescopically connected with the 95 pipe 13 and secured by a set-screw 15. The flue is provided with an elbow 16 to prevent escape of the light from above.

If oil is used in place of gas, a chimney 12 is employed, so as to deliver the draft at the 100

foot of the flame, as is required in all oil-burners. This chimney is preferably made of mica and can be readily slipped over the flue when required to be used.

5 If an incandescent electric lamp is used, the base 19 is made to contain the connections and socket 17 for a lamp 18 of suitable power—say four or eight candle power of the long thin variety—the tip of the globe to come 10 just below the mouth of the flue. A base and lamp so fitted may be substituted for the one fitted for gas shown in Fig. 1. If oil is the luminant, the alternative base, Fig. 5, is used. The base 20 is also the reservoir. 21 is the 15 socket for the burner 22. The burner 22 differs from the well-known burner of ordinary use only in a wick-tube prolonged sufficiently to lift the flame to the center of the lamp. 23 is the ordinary device for regulating the 20 wick, the rod being prolonged beyond the edge of the reservoir-base. With this burner an ordinary Welsbach chimney 24 may be used, resting upon the burner and encircling the flue. The burner need not be screwed 25 into the socket, but may be pressed in as in most modern lanterns.

By the use of my invention the temperature of the fluid will not rise to a point higher than can be comfortably borne by the hand 30 and a safe light can be emitted from forty to one hundred times as bright as would be given by any old-style lamp.

What I claim is—

1. In a lamp or lantern for a photographic 35 dark room, a transparent double-walled, cylindrical cell containing a fluid color-filter between the walls, the inner cylindrical wall being open at the top, a luminant within the inner cylinder, a ventilator through which air 40 is admitted into the luminant-chamber from above, and an outlet-flue leading from the interior of the luminant-chamber, substantially as described.

2. In a lamp or lantern for a photographic 45 dark room, a transparent, double-walled cylindrical cell containing a fluid color-filter between the walls, the inner wall being open both at the top and at the bottom, a luminant within the inner cylinder, a removable base for 50 the cell, means for preventing the escape of light over the upper surface of the fluid filter, and means for automatically introducing a current of air into the luminant-chamber from above, and an outlet-flue from the luminant-chamber, substantially as described.

3. In a photographic lamp or lantern for a 55 dark room, a luminant, an annular transparent cell surrounding the luminant and contain-

ing a fluid color-filter, a base which supports the cell and which prevents escape of light below the cell, a screen which prevents escape of light over the top of the filter, a ventilator through which air is admitted into the luminant-chamber from above, and blinds which prevent escape of light through the ventilator- 60 openings, substantially as described.

4. In a lamp or lantern for a photographic dark room, a double-walled, cylindrical, transparent cell containing a fluid color-filter between the walls, a luminant within the inner cylinder, means for automatically introducing a current of air from without at the top of the cell and conducting it down against the inner wall of the inner cylinder, and an outlet-flue from the inner cylinder, substantially as 70 described.

5. In a photographic lamp or lantern for a dark room, a luminant, an annular transparent cell surrounding the luminant and containing a fluid color-filter, a ventilating-box over 80 the top of said cell having air-ducts through which outside air is admitted into the interior of the cell, an outlet-flue leading from the interior of the cell through the upper part of the ventilator, and means for preventing escape 85 of light except through said filter, substantially as described.

6. In a photographic lamp or lantern for a dark room, a luminant, an annular transparent cell surrounding the luminant and containing a fluid color-filter; a ventilator over the 90 top of said cell through which outside air is admitted into the interior of the cell, an extensible outlet-flue leading from the interior of the cell through the ventilator, and means for varying the length of the outlet-flue, 95 substantially as described.

7. In a lamp or lantern for a photographic dark room, a double-walled, cylindrical, transparent cell containing a fluid color-filter between the walls and a luminant within the inner cylinder, a ventilator over the top of the cell through which outside air is admitted into the interior of the inner cylinder, an outlet-flue, and curved blinds which give direction 100 to the draft so that the current is given a downward spiral motion into the cylinder against the walls and thence out through the flue, substantially as described.

In testimony whereof I have affixed my signature in presence of two witnesses.

HERMAN F. SWARTZ.
